THERMOSTAT

**Earnest J. Dillman, Detroit, Mich., assignor to
Detroit Lubricator Company, Detroit, Mich., a
corporation of Michigan**

Application January 15, 1937, Serial No. 120,730

8 Claims. (Cl. 236—68)

In electrically operated systems and particularly low voltage systems provided by transformers, the voltage and therefore the amperage usually varies to some extent for different loads. 5 In control systems having thermostats operating on low voltage provided by transformers, it is usually required that the transformers be of a character which will not overheat in the event of a short circuit. It has been found that where 10 transformers made to meet the above requirement are employed, there is an appreciable difference in the voltage and therefore in the amperage for different loads. That is, under heavy loads which require high amperage from the 15 transformer the voltage will be relatively low, while for light loads that require comparatively low amperage from the transformer the voltage will be relatively high. As a result, in a control system having a thermostat provided with an 20 electric heater in circuit with the transformer for heating and influencing the operation of the thermostat, the effect of the heater will be different for different voltage or amperage. Or in other words, the same heater will not be as effective with one load as it will be for another, which 25 is of course objectionable.

Accordingly it is the principal object of my invention to provide a thermostat heated by electrically energized heating means in circuit with 30 a load and a transformer, and one in which the thermostatic element will receive a substantially constant heat input from the heating means irrespective of the magnitude of the load.

The invention consists in the improved construction and combination of parts, to be more 35 fully described hereinafter and the novelty of which will be particularly pointed out and distinctly claimed.

In the accompanying drawing, to be taken as 40 a part of this specification, I have fully and clearly illustrated my invention, in which drawing—

Figure 1 is a diagrammatic view of a temperature control system embodying my invention, and 45 Fig. 2 is a view of a modified form of my invention.

Referring to the drawing by characters of reference the numeral 1 designates in general my thermostat and the numeral 2 designates a control which may be a motor for controlling a heating apparatus. The thermostat 1 is preferably 50 operated on low voltage provided by a transformer 3 having the usual primary coil 4 and secondary coil 5. Main lead wires 6, 7 may connect the transformer primary 4 to the usual 110

v. line and lead wires 8, 9 may connect the transformer primary to the control 2. The thermostat 1 may control the circuit of the control 2 through controlling a relay 10 which, in the present instance, is the load, it being understood 5 however that the load may be any electrically operated device. The load or relay 10 may be of the conventional type having an electromagnet 11 and a switch 12, the switch being located in the lead wire 9 that leads from the transformer 10 primary 4 to the control 2.

My thermostat 1 preferably includes a supporting member or base 14 on which is mounted a temperature responsive element or bimetal blade 15. The blade 15 may extend in a general vertical direction and have its lower end secured to and adjacent the lower end of the base 14. A contact member 16 is mounted on and secured to the base 14 for cooperation with the blade 15 to control the circuit of the load or relay 10. The contact 16 is preferably in the form of 15 a screw and may be adjustably screw threaded into a metallic supporting member 17 that may be rigidly secured to the base 14. Preferably the contact 16 is located at one side of the blade 20 25 15 and adjacent the upper or free end thereof. The contact 16 is connected to the electromagnet 11 by a lead wire 18 and the electromagnet may be connected to the transformer secondary 5 by 30 a lead wire 19. Preferably a magnet 20, which 35 may be of the so-called permanent U-shaped type, is provided for attracting and holding the blade 15 in engagement with the contact 16. As is well known, the magnet 20 serves to determine 40 the differential operation of the thermostat 35 1 and also serves to prevent sparking between the blade 15 and the contact 16.

In order to provide a thermostat having electrically energized heating means in circuit with a load and with the circuit including a transformer which may be of the type embodying such construction that it has poor voltage regulation so that said thermostat will be subjected to a substantially constant heat from the heating means irrespective of the magnitude of the load, 45 I provide two heaters 21 and 22 and place the heater 21 in parallel circuit with the load or relay 10 and place the heater 22 in series circuit with the load. The heaters 21 and 22, which are electrical resistances, may be termed the 50 voltage and amperage heaters respectively, and may be mounted on the base 14 on opposite sides of the blade 15, as shown. The voltage heater 21, which may be a wire, has one end connected to the contact supporting member 17 and has 55

its other end connected by a lead wire 24 to the same side of the transformer secondary 5 as the load or relay 10. The other side or pole of the transformer secondary 5 is connected by a lead 5 wire 25 to one end of the amperage heater 22, and the other end of the amperage heater is connected to the blade 15, preferably by a jumper wire 26. Thus the heater 21 is in parallel circuit with the load or relay 10 and the heater 22 is 10 in series circuit with the load or relay 10.

When the blade 15 becomes dissatisfied and calls for heat, the blade will engage the contact 16 which will close the series circuit of the relay 10 and amperage heater 22 and also will close 15 the parallel circuit of the voltage heater 21. The series circuit of the relay 10 and amperage heater 22 is as follows: From the contact 16 through lead wire 18, relay electromagnet 11, lead wire 19, transformer secondary 5, lead wire 25, 20 amperage heater 22, blade 15 and back to the contact 16. The parallel circuit of the voltage heater 21 is as follows: From the contact 16 through the voltage heater 21, lead wire 24, transformer secondary 5, lead wire 25, heater 25 22, lead wire 26, blade 15 and back to the contact 16. Upon being energized the relay 10 will close the circuit of the control 2 which will operate to cause additional heat to be supplied to the room or other enclosed space to be heated.

30 The heaters 21 and 22 are selected so that together they will generate heat and raise the temperature of blade 15 to a desired temperature above the temperature of a room or other enclosed space to be heated. For the purpose of exposition it will be assumed that the combined heat generated by the two heaters will raise the temperature of the blade 2° F. above average room air temperature, and that the blade 15 is set 35 to close the circuit of the load or relay 10 when the blade is at a temperature of 69° F. and to open the circuit of the relay 10 when the blade is at a temperature of 73° F. The heaters 21 and 40 22 preferably are selected such that they will have a quick heating-up time and a quick cooling-down time. When the average room temperature has been increased by the heating apparatus to 71° F. the blade 15 will be 73° F. because of the 2° F. increase in the blade temperature above room air temperature caused by the heaters 21 45 and 22, and the blade will move out of engagement with contact 16 and open the circuits of the relay 10 and the heaters 21 and 22. The relay 10, upon being deenergized, will open the circuit of the control 2 which will act to stop 50 or decrease the heat input into the room. The heaters 21 and 22 will cool very quickly and after a short time the blade 15 will be heated only by the room air. When the temperature of the room, and therefore the temperature of the blade 15, decreases to 69° F., or whatever temperature it is set to call for heat, the blade will again 55 engage contact 16 to close the circuit of and energize the relay 10 and heaters 21 and 22. The purpose of the heaters 21 and 22 is to prevent unduly long operating periods of a heating apparatus or, in other words, the heaters compensate for the time period or time lag between the time of heat input to the room and the time when such heat input raises the temperature 60 of the blade 15 to the temperature for which it is set to cut-out the heating apparatus or stop 65 heat input to the room.

70 When my thermostat is employed with a load that requires only relatively low amperage, the voltage will be high and under these conditions

the voltage heater 21 will generate practically all of the total heat while the amperage heater 22, because of the low amperage passing through it, will contribute very little to the total heat. When my thermostat is employed with a load 5 that requires high amperage the voltage will go down and heater 21 will be less effective, but because of the higher amperage passing through the amperage heater 22 the total heating effect of both heaters will remain substantially constant. Thus it will be seen that my thermostat 10 may be employed with loads of varying magnitude, or with loads of different magnitude, without variation in the effectiveness of the blade's electric heating means. It will also be seen that 15 my thermostat eliminates the need of providing heaters of different resistances for different loads when using one standard type of transformer.

Referring now to Fig. 2 the modified form of 20 my thermostat shown in this view is similar to that shown in Fig. 1, but differs therefrom in that the blade 15 itself is utilized as one of the resistance heaters. In Fig. 2 the blade 15 is employed as the amperage heater, but it is to be understood that the blade may serve either 25 as the amperage heater or as the voltage heater, as desired.

What I claim and desire to secure by Letters Patent of the United States is:

1. In a control system, an electrical energy 30 supply, an electrical load, a temperature responsive means in circuit with said supply and said load and operable to control the circuit of the load, an electric heating means disposed to heat said responsive means for influencing the operation thereof, said heating means being in parallel circuit with said load, and a second electric heating means in heat transfer relation with said responsive means for influencing the operation thereof, said second-named heating means being 35 in series circuit with said load and also with said first-named heating means.

2. In a control system having a transformer and a load in circuit therewith, a contact member, a temperature responsive element cooperable 45 with said contact member to control the circuit of the load, said element also acting as a resistance heater for heating and influencing its own operation, and an electric heater in heat exchange relation with said element for heating 50 and influencing the operation of said element, said second-named heater being electrically connected to the transformer and in parallel circuit with the load and in series circuit with said element.

3. In a control system having a transformer and a load in circuit therewith, a contact member, a temperature responsive element cooperable 60 with said contact member to control the circuit of the load, said element also acting as a resistance heater for heating and influencing its own operation, and an electric heater in heat exchange relation with said element for heating and influencing the operation of said element, said second-named heater being electrically connected to the transformer and in parallel circuit with the load and in series circuit with said element, said second-named heater being controlled by said element and energized upon engagement by said element with said contact 65 member.

4. In a control system having a transformer and a load in circuit therewith, a contact member, a temperature responsive element cooperable with 70 said contact member to control the circuit of 75

the load, an electric heater connected to the transformer and in parallel circuit with the load, said heater being arranged in heat exchange relation with said element to heat and influence operation of said element, and a second electric heater for heating and influencing the operation of said element, said second-named heater being connected to the transformer and in series circuit with the load and with said first-named heater, both of said heaters being controlled by said element and energized when said element becomes dissatisfied.

5. In a control system, electrically operated means having a source of electrical energy, a temperature responsive element having a contact member, a contact member in circuit with said means and said source and cooperable with said first-named contact member, an electric resistance member positioned in thermal transfer relation to said element, a second electric resistance member positioned in thermal transfer relation to said element, said resistance members jointly being operable to supply heat to said element at a substantially constant rate irrespective of the current required by said operated means, said resistance members being in circuit with said source and said contact members, one of said resistance members being operable to supply heat to said element in direct proportion to the square of the sum of the current flow through said means and through the other of said resistance members, and the other of said resistance members being operable to supply heat to said element in direct proportion to the square of the voltage impressed on said electrically operated means.

6. In an electrical system for use with electrical loads requiring various rates of current flow including a source of electrical energy which may be subject to substantial voltage changes due to changes of current supplied, a temperature responsive means including a switch means and a combined temperature sensitive and electric resistance member for actuating said switch

means, a heating means positioned in thermal transfer relationship to said member, said heating means being directly responsive to the square of the voltage impressed on said electrically operated means, said combined member being directly responsive to the square of the total current flowing in said system, the heating effect of said combined members and said heating means being so proportioned relative to each other and to said energy source that the joint heating effect of said combined members and said heating means is substantially constant regardless of the current supplied to the electrical load.

7. In an electrical system, an electrically operated apparatus, means in series circuit therewith and operable to control the operation thereof, means operable during a condition of said apparatus for maintaining a combined heating effect on said control means, said heating effect being proportional to the square of the current controlled by said means and to the square of the voltage impressed on said apparatus irrespective of changes in the current required by said apparatus, said last-named means producing a substantially constant heating effect on said first-named means irrespective of any change in current which might be required by said apparatus.

8. In a control system, an electrically operated apparatus, means in series circuit with said apparatus and operable to make and break an electrical circuit to said apparatus, said means being responsive to a heating effect variable with the square of the magnitude of the current controlled thereby, a second heating means in parallel circuit relation with said apparatus and effective to supply heat according to the square of the voltage across said apparatus irrespective of changes in current required thereby, said second-named means being so proportioned relative to said first-named means that the combined heating effect of said first-named and said second-named means is substantially constant regardless of the magnitude of the current required by said apparatus.

EARNEST J. DILLMAN.
